United States Patent Office

Des. 189,132
Patented Nov. 1, 1960

189,132

STADIUM SEAT

Douglas S. Brinkley, 10746 Kinloch Road,
Silver Spring, Md.

Filed Feb. 16, 1960, Ser. No. 59,416

Term of patent 14 years

(Cl. D15—8)

Fig. 1.

Fig. 2.

Figure 1 is frontal perspective view of a stadium seat embodying my new design; and

Figure 2 is perspective view taken from the rear of the same.

The essential features of the design are shown in solid lines on the drawing.

I claim:

The ornamental design for a stadium seat, substantially as shown and described.
